UNITED STATES PATENT OFFICE.

JOSEPH WARREN JONES, OF ST. LOUIS, MISSOURI.

METALLIC BUILDING STRUCTURE.

1,311,820.

Specification of Letters Patent. Patented July 29, 1919.

Application filed April 26, 1916. Serial No. 93,585.

To all whom it may concern:

Be it known that I, JOSEPH WARREN JONES, a citizen of the United States, residing at the city of St. Louis, State of Missouri, have invented certain new and useful Improvements in Metallic Building Structures, of which the following is a full, clear, and exact description, such as will enable others skilled in the art to which it appertains to make and use the same, reference being had to the accompanying drawings, forming a part of this specification.

This invention relates generally to metallic building structures and more specifically to an improved construction for a structural member which may be variously employed as a column, strut member and the like.

As is well known, in various metallic structures, such as bridges, towers, framing for buildings and the like, numerous members are employed as columns, struts, or bracing elements, which are so disposed as to carry longitudinal stresses, and the most important factors of which, therefore, are a sufficient amount of metal and such a disposal of same as to have a sufficient radius of gyration to lend the necessary stability. In present practice, such members are frequently formed as laced or latticed members, common forms of which consist of two or more commercial shapes joined by lacing or latticing of narrow strips riveted to the members and serving to keep them properly spaced apart to give the necessary stiffness or stability.

The principal object of my present invention is to provide an improved construction for a structural member of this sort, by virtue of which construction the cost of the member is materially decreased, and a member having maximum strength, for the amount of material employed, is formed.

A further object of my invention is to provide a construction in which standard commercial rolled shapes of a wide variety of types and weights may be employed.

A further object of my invention is the provision of a structural member of the sort described which may be easily fabricated for different particular uses, and which lends itself particularly to structural uses in having a form such as to facilitate its connection to other members in the structure

in any of the fashions now commonly employed. 55

A still further object of my invention is the provision of a structural member which is particularly adapted for use in reinforced concrete construction, because of the facilities which it affords for the disposal, accommodation, and attachment thereto of concrete reinforcing rods.

Other and further objects of my invention will be obvious or pointed out hereinafter, 65 reference being had to the accompanying drawings forming a part of this specification, and in which

Figure 1 is a side elevation of a channel member of a sort which may be employed 70 in the construction of my improved member;

Fig. 1^a is a cross section thereof;

Fig. 2 is a side elevation of the same member after it has been cut and pressed in the process of manufacturing my improved 75 member;

Fig. 2^a is a cross section thereof, being taken on line 2—2 of Fig. 2;

Fig. 3 is a top view of the member illustrated in Figs. 2 and 2^a; 80

Fig. 4 is a side elevation of one form of my improved structural member;

Fig. 4^a is a cross section of the same taken approximately on the line 4—4 of Fig. 4;

Fig. 5 is a similar cross section of a modified form of my improved member; 85

Fig. 6 is a similar section of a second modification;

Fig. 7 is a similar section of a third modification; 90

Fig. 8 is a similar section of a fourth modification.

Figs. 9 to 12 inclusive are side elevations illustrating various modified forms of the connecting system. 95

Fig. 12^a is an end elevation of the member illustrated in Fig. 12;

Fig. 13 is a side elevation of a further modification of my invention designed specifically for a pole or a post. 100

Fig. 14 is a front elevation of the same.

Referring to the drawings more specifically, the various parts being designated throughout by similar reference characters, it will be understood that in the manufacture of my improved member, I may employ any of a wide variety of commercial structural shapes; that illustrated in Figs. 1 and

1^a being a simple channel member having a web *w* and marginal flanges *f*. As illustrated in Fig. 2, portions of the webs of members of the selected form are punched out or slotted as shown, the displaced portions being deflected to one side of the normal plane as shown in Figs. 2^a and 3, but remaining integral with the web at one end. Two of the members so formed, which I will 10 designate A and B respectively, are then placed together as illustrated in Figs. 4 and 4^a, with the deflected portions *s* in contact, and these deflected portions or spacing strips as I will call them, are secured together, as 15 by spot welding, or riveting, or in any other suitable fashion. The members A and B, as is obvious, may be disposed parallel or in diverging relationship. When connected as described, the members form a 20 unitary structural member in which the constituent members A and B are the principal load carrying elements, and the spacing strips *s* are connections which maintain the members A and B in proper disposal and relationship. The structural member so 25 constructed will form an effective strut or column, and will possess the necessary stiffness and stability against longitudinal stresses, and also permit of considerable resistance to transverse and torsional stresses.

Of course, the width and length of the spacing strips may be varied as desired, as 30 may also the degree and form in which they are deflected from the webs of the members A and B. However, bars formed with spacing strips of a given length, may be utilized to form structural members of different radii by varying as desired the distance at which they are spaced apart and the 35 extent to which the spacing strips are overlapped before they are connected.

In Figs. 5, 6 and 7, I have shown a variety of shapes, all standard, which may be utilized. In Fig. 5, it will be observed that 40 instead of having the spacing strips deflected from the web in the same direction as the flanges, they are deflected oppositely thereto so that in the completed member all the flanges extend outwardly.

50 In Fig. 6, I illustrate the use of an angle bar as the member A' and an I-beam as the member B'.

In Fig. 7, I illustrate the use of simple plates as the members A² and B².

55 In Fig. 8, the members A³ and B³ are the flanges of a specially shaped channel which is U-shaped in cross section, and the spacing strips *s* are punched out adjacent the margins of said flanges.

60 In Fig. 9, I illustrate the manner in which the spacing strips may be connected by rivets, and show also how they may be disposed perpendicular to the webs, or at any desired intermediate angle.

65 In Fig. 10, I illustrate a modification

wherein the spacing strips instead of being connected to each other, are connected to the web of the opposite member.

In Fig. 11, I show the spacing strips connected by butt welding.

In Figs. 12 and 13, I show a construction wherein the spacing strips are longitudinally corrugated, or provided with a rib, whereby they are materially stiffened.

In Figs. 13 and 14, I illustrate an application of my invention wherein the members A⁴ and B⁴ are portions of an integral member which is bent upon itself so as to bring its end portions opposite to each other. The connecting strips *s* are punched from the 80 original member and connected across between the opposite portions. A cross section of Fig. 13 would be similar to Fig. 7, although the member, of course, could be a channel or other shape.

85 In members formed in the fashion illustrated and above described, it will be observed that two oppositely disposed members, either separate or integral, are used, which members provide the necessary metal 90 to carry the stress to which the structural member is designed to be subjected. These oppositely disposed members in my improved structure are connected by spacing strips, which strips are formed from portions of the members themselves. It will be 95 observed, moreover, that while this construction requires the use of no material in addition to the original bar members it forms a structural member of maximum strength 100 for its weight as the deflected portions or connecting strips are taken from those parts of the bar members which are least effective in supplying stiffness and stability. Besides producing a member having great 105 strength and stability for the amount of material required, this form of construction materially decreases the amount of labor necessary in the manufacture of structural members designed for the use contemplated, as it is not necessary in the manufacture of my improved structural member to bolt up all of the connections preliminary to the operation of permanently securing the constituent parts together.

110 It is obvious that this construction is susceptible of wide application, being useful not only as column or strut members in building constructions, but useful also as a reinforcement for concrete posts, beams, etc., to which uses it is particularly adapted by virtue of the facility with which other forms of reinforcements, such as rods may be associated with it, passed through its apertured portions and connected to it.

115 While I have shown in the drawings a number of forms in which my invention may be embodied I am aware, of course, that the structure is susceptible to further variations, modifications and adaptations without 120

departing from the invention, the scope of which is indicated in the following claims.

What I claim is:

1. A metallic structural element comprising side bars or load carrying members, said members having web portions oppositely disposed, a series of tongues cut from said web portions and laterally deflected into coöperative relation and joined together to form spacing and bracing connections between the load carrying members. 5
2. A metallic structural element comprising side bars or load carrying members, said members having web portions oppositely disposed, pairs of tongues oppositely cut from said web portions and laterally deflected into coöperative relation and joined together to form spacing and bracing connections between the load carrying members. 10
3. A metallic structural element comprising side bars or load carrying members, said members having web portions oppositely disposed, a series of tongues cut from said web portions and laterally deflected into coöperative relation and joined together to form spacing and bracing connections between the load carrying members. 15
4. A metallic structural element comprising side bars or load carrying members, said members having web portions oppositely disposed, a series of tongues cut from said web portions and laterally deflected into coöperative relation and joined together to 20 form spacing and bracing connections between the load carrying members, said tongues being formed with beads which operate to stiffen them intermediate the load carrying members. 30
5. A metallic structural element comprising side bars or load carrying members disposed side by side and spaced apart and having web portions oppositely disposed, a series of tongues cut from said web portions and laterally deflected into coöperative relation and joined together to 35 form spacing and bracing connections between the load carrying members. 40

In witness whereof I have hereunto set my hand this 24th day of April, 1916. 45

J. WARREN JONES.
